DESIGN FOR A BUTTER SUBSTITUTE MIXING DEVICE

Ralph R. Auerswald, San Diego, Calif.

Application January 20, 1945, Serial No. 117,518

Term of patent 14 years

(Cl. D44—29)

To all whom it may concern:

Be it known that I, Ralph R. Auerswald, a citizen of the United States of America, residing at San Diego, in the county of San Diego and State of California, have invented a new, original, and ornamental Design for a Butter Substitute Mixing Device, of which the following is a specification, reference being had to the accompanying drawing forming part thereof.

Figure 1 is a side elevational view of my new design for butter substitute mixing device; Fig. 2 is a top end view thereof; and Fig. 3 a bottom end view.

I claim:

The ornamental design for a butter substitute mixing device, substantially as shown.

RALPH R. AUERSWALD.
